F. D. MOORE, OF EDRAY, WEST VIRGINIA.

Letters Patent No. 74,115, dated, February 4, 1868.

IMPROVEMENT IN HAND-SPINNING-MACHINE.

The Schedule referred to in these Letters Patent and making part of the same.

TO ALL WHOM IT MAY CONCERN:

Be it known that I, F. D. MOORE, of Edray, in the county of Pocahontas, and State of West Virginia, have invented a new and useful Improved Hand-Spinning Machine; and I do hereby declare that the following is a full, clear, and exact description thereof, which will enable others skilled in the art to make and use the same, reference being had to the accompanying drawings, forming a part of this specification, in which—

Figure 1 represents a side view of my improved spinning-machine.

Figure 2 is a detail.

Figure 3, a plan or top view.

Figure 4, a vertical cross-section, taken in the line $x\ x$, fig. 1.

Figure 5, a horizontal section through a part of the machine, in the line $y\ y$, fig. 3, showing a detail.

Similar letters of reference indicate corresponding parts.

This invention relates to a new and useful improvement in the construction of a machine for spinning yarns of wool or other fibre by hand, and consists in the combination and arrangement of an ordinary rim spinning-wheel mounted on a bench, and banded to a driving-pulley with shifting-pulleys, a movable spindle-head running back and forth on a track or way, and with reversing-gear, whereby a person may sit at the side of the rim-wheel and, by the reciprocating movements of the spindle-head, while the rim-wheel is turned by hand, draw the roping, twist the yarn, and wind it on the "broach," by a repeated series of operations, and thus, with very little labor, accomplish much more work than with the ordinary spinning-wheel, while the yarn will be of superior quality, as respects the evenness and regularity of the twist.

A is a long bench, say fifteen feet, for supporting the machinery, at the right hand end of which, with regard to the operator, is placed the rim-wheel B, hung in a standard, a , that is adjusted at the foot by a slide, b , to regulate the tension of the band c , connecting the wheel with the driving-pulley C hung in the middle of a spindle, d , having bearings in the top of the standards $e\ e$, on each side of the bench A. On the same spindle, d , are placed two loose pulleys, $g\ g'$, one on each side of the driving-pulley C, with and from which they are alternately engaged and disengaged by clutches, $h\ h'$, for giving different movements to the carriage and spindle-head D, as hereinafter described.

E is a treadle, connected by a cord, k , that runs over a pulley, k' , with a long upright lever, l , pivoted at the lower end to the leg F of the bench, and at the upper part connected with a horizontal slide, m , that carries a rod, n , placed obliquely to the line of its movement, so that it works a transverse slide, m' , back and forth to engage and disengage the pulleys $g\ g'$, as required, by means of arms $m^2\ m^3$ fastened on to those pulleys operating the clutches $h\ h'$.

At the left-hand end of the bench are placed two standards, $i\ i'$, in which is hung a pulley, G. The standards $i\ i'$ are connected with the bench in such a manner that they can be moved to regulate the tension of the band $s\ s$, which passes over the pulley G from the pulley g' , and gives motion to the spindle, as hereinafter described. Another standard, j , is placed on the front side of the frame A, just forward of the standard i , which supports a large pulley, H.

On the front side of the bench or main frame, A, is made fast vertically a broad board, I, the upper edge of which serves as a track for the two wheels $o\ o$ of the spindle-head carriage J, while the lower edge of the board serves as a guide-way for the arm p , extending down from the carriage D, to keep it in an upright position. The spindle-head D supports a large driving-pulley, K, on the shaft of which is a small double pulley, q, around which passes the band $s\ s$, that also passes under a small pulley, r, directly below the pulley q, for the purpose of saving friction and wear of the band. The pulley K is banded directly to the spindle t, which is to be so attached to the head that it may be moved to adjust the tension of the driving-band. The carriage K is attached to a band, s^1 , that passes over the pulleys g and H, to give it motion back and forth on the way-board I.

A square-toothed ratchet-wheel, u, is placed on the shaft of the pulley G, operated by a latch-dog, u^1 , attached to a vertical slide-bar, v, working in the front standard i . In the lower end of the slide-bar v is a pin, 3, that catches under the arm w of a dog, w^1 , which is fastened upon another vertical slide-bar, v^1 , working in the standard j . The slide-bar v^1 is operated on by a long spring-hook, v^2 , that is pivoted to the standard j , and catches against a pin, 4, in the lower end of the slide-bar v^1 , to hold the slide-bar up when it has been raised by

the incline 5, enabling the slide-bar to engage and disengage the dog w^1 from a ratchet-wheel, u^2 , placed on the shaft of the pulley H , to operate as hereinafter described. On the same shaft, by the side of the ratchet-wheel u^2 , is placed a check-pulley, x , that is banded to a pin, y , that is set in the upper end of a slide-bar, v^3 , that also works vertically in the face of the standard y , and is held down by a spring, a' , at the lower end, or by a weight that may be hung to it, in order to act on the check-pulley x , as hereinafter described. A slotted bar, z , is suspended at its upper end to the pin y in the slide-bar v^3 , and its lower slotted or forked end works upon a pin, y^2 , set in the end of a long horizontal slide-bar, v^4 , that runs along the lower edge of the way-board I, and is connected at its forward end to the long lever l , from which it receives motion to operate the machinery previously described. On the face of the way-board I are set the guard stop-pins 1 2, to hold the carriage J stationary at each end of its traverse movement.

A ratchet-wheel, u^3 , is placed on the shaft d , on the side of the pulley g' , acted on by a spring-dog, w^2 , fig. 4, to prevent the pulley from turning to the left when disengaged from the drawing-pulley C.

The operation of this machine is as follows: The spinner sits in front of the rim-wheel B, with one foot on the treadle E, using the right hand to turn the wheel, in the usual way, and the left hand to manage the yarn. Turning the wheel slowly to the right, the carriage J being up to the forward limit of its movement, the roll of wool is attached to the spindle t , after which the treadle is gently pressed to draw the lever l forward to the right, carrying with it the slide m and the diagonal rod n for disengaging the pulley g' from the driving-pulley C, carrying it against the spring-dog w^2 , to stop the pulley g' and prevent it from turning to the left, while at the same time the pulley g engages the driving-pulley C. The forward movement of the lever l also draws the slide-bar v^4 forward at the same time, by which the slotted bar z is moved, in such a manner that it raises the vertical slide-bar v^3 , and releases the check-wheel x , allowing thereby free movement to the pulley H , and consequently also gives motion to the carriage J, which moves back to the left on the way-board I, by the pulling-action of the band s^1 that passes over the pulleys H g , and is fastened at both ends to the carriage. As the carriage travels back, for drawing the roping, the spindle receives a gentle motion from the pulley g , that travels over the stationary band s , thereby giving also to the roping a slight twisting while it is drawn. But, as the carriage J approaches its station to the left hand of the machine, it reverses the lever l , by means of a check-line, s^2 , which connects the lever and the carriage, thus drawing the slide m back to disengage the pulley g and engage the pulley g' with the driving-pulley C. The carriage stands still at its left-hand station long enough to twist the yarn by the accelerated motion of the spindle, imparted by the revolution of the pulley g' , so soon as it is engaged. While the thread is twisting, the latch u^1 of the square-toothed ratchet-wheel u is in position to the right, but, as soon as the thread is twisted enough, a slight backward motion is necessary to back the thread down on the "broach" ready to be taken up. This movement, which is accomplished by the operator turning the wheel B slightly in the opposite direction, carries the latch u^1 over to the left side of the ratchet-wheel, thus raising the sliding bar v , to which the latch is attached, and bringing the pin 3 at the lower end of the sliding bar up against the arm w of the dog w^1 , releasing it from the ratchet-wheel u^2 , when at the same time the vertical slide-bar v^3 is raised sufficiently to let the spring-hook v^2 catch under the pin 4, at the lower end of the slide-bar, and keep the dog w^1 clear of the ratchet-wheel u^2 , while the carriage moves again to the right. The carriage is drawn to the right by the tension of the thread. So soon as the gearing is thus again changed, and the horizontal slide v^4 is moved to the right, the pin 5, on the left end of the slide-bar, catches against the lower end of the spring-hook v^2 , carrying it off to the right, disconnecting it from the pin 4, which then rests upon the end of the slide v^4 , where it remains until another movement of the slide v^4 to the left allows the vertical slide v^3 to fall, when the pawl w^1 is brought into connection with the ratchet u^2 . The carriage is then in its first position again, and the operation is repeated.

Having thus described my invention, what I claim as new, and desire to secure by Letters Patent, is—

1. The combination of the pulleys g g' , the rod n , the slide m , with the uprights m^2 , the lever l , and the treadle E, arranged and operating substantially as and for the purposes herein described.
2. The slide-bar v^4 , operated by the lever l , in combination with the slotted swing-bar z and the spring-hook v^2 , arranged and operating as and for the purposes set forth.
3. The ratchet-wheel u^3 and spring-dog w^2 , combined with the pulley g' , and operating substantially as and for the purpose specified.
4. The combination of the horizontal sliding bar v^4 , the slotted swing-bar z , the vertical slide v^3 , and the check-pulley x , arranged and operating substantially as and for the purposes herein described.
5. The square-toothed ratchet-wheel u , the dog u^1 , the slide-bar v , the dog w^1 , the slide-bar v^1 , the spring-hook v^2 , and the slide-bar v^4 , combined and operating substantially as and for the purposes set forth.
6. The check-pulley x , the slide v^3 , the spring a' , and the slotted bar z , or its equivalent, combined and operated as and for the purpose specified.

The above specification of my invention signed by me, this 31st day of July, 1867.
